UNITED STATES PATENT OFFICE.

LOUIS LANE AND WILLIAM H. LANE, OF NEWARK, OHIO.

FIRE-PROOF LATHING.

SPECIFICATION forming part of Letters Patent No. 331,643, dated December 1, 1885.

Application filed June 12, 1885. Serial No. 168,488. (No model.)

To all whom it may concern:

Be it known that we, LOUIS LANE and WILLIAM H. LANE, citizens of the United States, residing at Newark, in the county of Licking and State of Ohio, have jointly invented certain new and useful Improvements in Fire-Proof Lathing, of which the following is a specification.

Our invention consists in the combination of strips of sheet metal, with an interlacing of wires so arranged as to form a continuous sheet or roll. The strips may be crimped or corrugated, and may be perforated. These strips are placed at intervals sufficient to allow the mortar to pass between them and form the clinch on the back. The strips are made narrow, thus affording frequent and perfect support for the mortar. The strips are held firmly in position by the wires being twisted together between the strips, which also serves to make the strips "work" together, so that they are more rigid, and also prevents sagging between supports on partitions. We thus form a sheet of rigid metal lathing, which can be more rapidly applied than the separate strips, and which affords a better clinch for the plaster, as the strips can be made narrower.

In the drawings, Figure 1 is a cross section, Fig. 2 is a perspective, and Fig. 3 a view in detail, of my invention.

A is the corrugated strip of sheet metal interlaced by the wires B B, which are twisted, as shown at D. These wires occur at intervals, as shown. The lathing is attached by securing it to the furring with the clip E, which serves to take up any slack in the wires, thus stretching them tightly. Any other suitable device may be used instead of E. In the other figures the same parts are indicated by the same letters as in Fig. 1.

Having described our invention, what we claim as new, and desire to secure Letters Patent for, is—

A sheet of metallic lathing composed of strips of sheet metal woven together by wire-warp strands, which are twisted together where they cross, substantially as before set forth.

LOUIS LANE.
WILLIAM H. LANE.
